RAILWAY SIGNALING SYSTEM

Henry S. Young, Wilkinsburg, Pa., assignor to The
Union Switch & Signal Company, Swissvale, Pa.,
a corporation of Pennsylvania

Application January 26, 1942, Serial No. 428,219

5 Claims. (Cl. 246—63)

My invention relates to a railway signaling system of the type shown in Letters Patent of the United States No. 1,822,497 issued September 8, 1931, to H. S. Loomis, and employing train-carried governing means adapted to cooperate with train controlling devices located in the trackway.

Signaling systems of this type have inductors located at the entrance of each track section. Each inductor has a U-shaped core having a winding thereon while the inductors cooperate with train-carried equipment so that if at the time the train passes over an inductor the circuit of the winding of the inductor is open the train-carried equipment will operate to apply the brakes, while if at the time the train passes over an inductor the winding of the inductor is short circuited the train-carried equipment is not affected.

It is customary in systems of this kind to arrange the wayside apparatus so that the circuit of the winding of the inductor for each track section is controlled in accordance with the aspect displayed by the wayside signal for that section in such manner that the winding of the inductor is short circuited when the signal displays its clear indication and is open circuited at all other times.

It has heretofore been proposed to check the circuits of the inductor windings by including each winding in the pick-up circuit of the relay which causes the associated wayside signal to display its clear indication. This prevents the display of a clear indication by a signal if the circuit of the winding of the associated inductor is defective and thus prevents an emergency application of the brakes on a train when the train passes the inductor associated with a signal displaying a clear indication.

The systems heretofore provided have been arranged so that one terminal of the inductor winding is permanently connected to one of the line wires over which energy is supplied from the adjacent signal in advance to the relay which controls the clear signal indication. This wire may also serve as the common wire for other circuits and may be grounded so that if a cross to ground develops with the wire leading from the other terminal of the inductor winding the inductor winding will be short circuited regardless of whether the relay controlling the clear signal indication is energized or not. If this condition develops and a train should pass the inductor at a time when the associated signal is displaying its stop or its caution indication the

train-carried equipment will not function to apply the brakes.

It is an object of this invention to provide a signaling system of the type described and incorporating improved means to control the circuits of the inductor windings.

A further object of the invention is to provide a system of the type described which is arranged so that when the track relay for a section is released the circuit of the winding of the inductor for that section is isolated from the signal control circuits to thereby minimize the possibility that this winding will be improperly short circuited.

Another object of the invention is to provide an improved system of the type described which is arranged so that the circuit of the winding of the inductor for each section is checked just prior to passage of a train over the inductor to thereby minimize the possibility that a defect will develop in the circuit of the inductor winding between the time the circuit is checked and the time at which a train passes over the inductor.

Other objects of the invention and features of novelty will be apparent from the following description taken in connection with the accompanying drawings.

I shall describe three forms of railway signaling systems embodying my invention, and shall then point out the novel features thereof in claims.

In the drawings Fig. 1 is a diagram of a stretch of railway track equipped with a signaling apparatus embodying my invention, and

Figs. 2 and 3 are diagrams showing modifications which I may employ.

Similar reference characters refer to similar parts in each of the several views.

Referring to Fig. 1 of the drawings there is shown therein a stretch of track having track rails 1 and 2 over which traffic normally moves in the direction indicated by the arrow, that is, from left to right. The rails of the track stretch are divided by insulated joints 3 into the customary track sections for signaling purposes. These sections are designated 3T, 4T, and 5T. Each section is provided with a track circuit consisting of a track battery connected across the section rails at the exit end of the section, and a track relay, designated TR with an appropriate prefix, connected across the section rails at the entrance end of the section.

Each track section has at the entrance end thereof a suitable wayside signal designated S

with a suitable prefix. These signals may be of any appropriate type and as shown in Fig. 1 are of the semaphore type, and each is capable of displaying a proceed, a caution, and a stop indication. Each signal has associated therewith a contact 25 which is governed in accordance with the position of the semaphore arm. Each such contact is arranged so that the contact is open when the semaphore arm is in its horizontal or stop position, and is closed when the arm is in its 45° or caution position or its 90° or clear position, or is intermediate its caution and clear positions.

Each signal has associated therewith a relay TP and a relay D which cooperate as explained below to control the signal and to control the supply of energy to the adjacent signal in the rear. Each signal also has associated therewith a battery M, while the negative terminal C of each battery is connected to a common line wire 10 which extends throughout the track stretch.

Each track section is provided with an inductor K which is located in the trackway a short distance in the rear of the entrance end of the section. Each inductor is adapted to cooperate in the usual manner with train-carried apparatus of any appropriate design. The train-carried apparatus is not a part of this invention and has not been shown in order to simplify the disclosure.

The equipment is shown in the condition which it assumes when the track stretch is vacant. As the stretch is vacant the track relays are picked up. As relay 5TR is picked up the circuits of the relays 5TP and 5D are complete and the relay 5TP is energized over the circuit which is traced from terminal B of the battery 5M, wire 11, contact 12 of relay 5TR, contacts 14 and 15 of relay 5D in multiple, contact 16 of relay 5TR, winding of relay 5TP, and a branch of wire 10 to terminal C of battery 5M.

As relay 5TP is energized its contact 20 establishes the circuit of relay 5D to permit energy to be supplied to this relay from the battery associated with the adjacent signal in advance.

In addition, contact 22 of relay 5TP is closed and establishes connection from wire 11 to wire 29 so that energy is supplied to the caution operating circuit of the signal 5S.

As relay 4D is energized energy is supplied to the clear operating circuit of signal 5S to cause the semaphore arm of this signal to remain in its vertical position to provide the proceed or clear indication. The circuit for supplying energy to the signal is traced from terminal B of the battery 5M through front contact 22 of relay 5TP, wire 29, front contact 23 of relay 5D, wire 24, signal 5S and a branch of wire 10 to terminal C of the battery 5M.

As the signal 5S is displaying its clear or proceed indication signal operated contact 25 is closed and energy from the battery 5M is supplied to the relay 4D over the circuit which is traced from terminal B of the battery through wire 11, signal contact 25, front contact 27 of relay 5TP, wire 28, front contact 20 of relay 4TP, winding of relay 4D, and common wire 10 to terminal C of the battery 5M.

As the contacts of relay 5D are picked up, its contacts 14 and 15 short circuit the winding of the inductor 5K as is obvious from the drawings.

The equipment associated with signal 4S is in the same condition as that associated with signal 5S and the circuits at this location will not be traced in detail.

When a train moving in the normal direction

of traffic passes through the track stretch the locomotive carried apparatus will not be affected by the inductors 4K and 5K as the windings of these inductors are short circuited.

5 When the train enters section 4T track relay 4TR releases and its contacts 12 and 16 interrupt the circuit of the relay 4TP so that contact 29 of relay 4TP interrupts the circuit of relay 4D, while contact 27 of relay 4TP interrupts the supply of energy to the wire 28 leading to the adjacent signal in the rear and contact 22 of relay 4TP interrupts the supply of energy to the caution and clear operating circuits of signal 4S so that this signal displays its stop indication. As relay 4D is deenergized its contacts 14 and 15 release and open the circuit short circuiting the winding of inductor 4K.

Accordingly when section 4T is occupied signal 4S displays its stop indication, while the winding of inductor 4K is open circuited so that the train-carried apparatus on a following train will cause the brakes on the train to be applied if the train passes over the inductor.

When the train advances into section 5T the signal for this section is placed at stop and the winding of the inductor 5K is open circuited, while the supply of energy to wire 28 leading to signal 4D is cut off.

When the train vacates section 4T track relay 4TR picks up and a circuit including the winding of inductor 4K in series therewith is established to energize the relay 4TP. This circuit is traced from terminal B of battery 4M through wire 11, front contact 12 of relay 4TR, winding of inductor 4K, contact 16 of relay 4TR, winding of relay 4TP, and wire 19 to terminal C of the battery. Accordingly, if the circuit of the inductor winding is complete the relay 4TP will be energized in series with this winding, but if the circuit of the inductor winding is defective the relay 4TP will remain released.

When the relay 4TP picks up its contact 22 establishes connection from terminal B of the battery 4M to the caution operating wire 29 for signal 4S and this signal displays its caution indication while contact 25 is closed so that connection is established from terminal B of battery 4M to wire 28 leading to the adjacent signal in the rear. As contact 20 of relay 4TP is picked up energy may be supplied to relay 4D, but as long as section 5T is occupied energy is not supplied to the wire 28 leading to relay 4D and this relay remains released.

At this time the terminals of the winding of the inductor 4K are connected together through the winding of relay 4TP and the battery 4M, but the resistance of this connection is so high that the inductor functions as though its circuit were open, and if a train passes over the inductor the train-carried apparatus will operate to apply the brakes unless it is suppressed by the engineer.

When the train vacates section 5T the equipment for this section operates in the same manner as that for section 4T and relays 5TR and 5TP pick up while energy is supplied to the caution operating circuit for signal 4S, and contact 27 of relay 5TP and signal operated contact 25 establish connection from terminal B of battery 4M to wire 28 leading to relay 4D. Accordingly, the contacts of relay 4D become picked up and its contact 23 establishes the clear or proceed operating circuit for the signal 4S so that the signal displays its proceed indication while contacts 14 and 15 of relay 4D short circuit the winding of

the inductor 4K so that train-carried equipment will not be affected by the inductor.

On picking up of the contacts of relay 4D and short circuiting of the winding of the inductor 4K the current to energize the relay 4TP is supplied through contacts 14 and 15 of relay 4D instead of through the winding of the inductor.

If at the time the train vacates section 4T the circuit of the winding of the inductor 4K is defective, the relay 4TP will not be energized and its contacts will remain released and will not establish the caution operating circuit of the signal 4S and this signal will continue to display its stop indication. In addition, as signal 4S is at stop and relay 4TP is released energy is not supplied to wire 28 leading to the adjacent signal in the rear and that signal continues to display its caution indication.

Furthermore, as relay 4TP is deenergized when the circuit of the winding of the inductor 4K is defective, the circuit of the relay 4D is interrupted and this relay remains released when section 5T is vacated and energy is supplied to line wire 28 leading to the relay 4D.

It will be seen, therefore, that the system shown in Fig. 1 is arranged so that the circuit of the winding of the inductor for a section is checked every time a train passes through the section, and if the circuit of the inductor winding is defective, the signal for the section will continue to display its stop indication after the section is vacated while the adjacent signal in the rear will display its caution indication.

Accordingly, a signal cannot display an indication inconsistent with the condition of the associated inductor, and a defective inductor cannot produce an unexpected application of the brakes on passage of a train over the inductor at a time when the associated signal is displaying its clear or proceed indication.

In addition, it will be seen that the system is arranged so that when the contacts of the relay D are released the circuit of the winding of the associated inductor is isolated from the signal circuits and a ground on one of the wires leading from the inductor winding cannot result in short circuiting of an inductor winding.

In Fig. 2 of the drawings there is shown a modification which I may employ in place of that shown in Fig. 1. This modification is similar to that shown in Fig. 1, but differs therefrom as a repeater relay is provided for the distant signal control relay and this repeater relay checks the circuit of the inductor winding.

The equipment of Fig. 2 is shown in the condition which it assumes when the track stretch is vacant. At this time the track relays are picked up and contact 30 of each track relay establishes the circuit through which energy is supplied over the wires 28 to the relays DR. Accordingly the contacts of the relays DR are picked up and their contacts 31 and 32 establish the circuit to energize the associated relay DP from the battery M at that location. The circuit for energizing the relay 4DP is traced from terminal B of the battery 4M through front contact 31 of relay 4DR, contacts 34 and 35 of relay 4DP in multiple, contact 32 of relay 4DR, and winding of relay 4DP to terminal C of the battery 4M.

As the contacts of the relay DP are picked up, the contact 37 of each relay establishes the clear or proceed operating circuit for the associated signal and the signal displays its proceed indication, while its contact 25 establishes connection from terminal B of the associated battery

to the wire 28 leading to the adjacent signal in the rear.

In addition, the contacts 34 and 35 of each relay DP short circuit the winding of the associated inductor K so that a train may pass over the inductor without delay.

When a train moving in the normal direction of traffic, that is, from left to right, enters section 4T track relay 4TR releases and its contact 38 interrupts both the caution and proceed operating circuits for the signal 4S, while its contact 39 interrupts the circuit of wire 28 leading to the adjacent signal in the rear. The signal 4S, therefore, displays its stop indication and its contact 25 is opened to additionally interrupt the circuit of the wire 28. On release of track relay 4TR its contact 30 interrupts the circuit of relay 4DR so that contacts 31 and 32 of relay 4DR release and interrupt the circuit of relay 4DP. Accordingly, the contacts of relay 4DP release and its contact 37 additionally interrupts the clear operating circuit of the signal 4S, while contacts 34 and 35 of the relay interrupt the circuit short circuiting the winding of the inductor 4K.

On entrance of the train into section 5T track relay 5TR releases and causes release of relays 5DR and 5DP, while the signal 5S goes to stop.

When the train vacates section 4T track relay 4TR picks up and its contact 38 establishes the caution operating circuit of the signal 4S and this signal displays its caution indication, while its contact 25 is closed and cooperates with front contact 39 of relay 4TR to supply energy to the wire 28 leading to the adjacent signal in the rear.

At this time contact 30 of relay 4TR is closed to permit energy to be supplied to relay 4DR, but as signal 5S is at stop and relay 5TR is released energy is not supplied to wire 28 leading to relay 4DR and this relay remains released and interrupts the circuit of relay 4DP. Accordingly, relay 4DP remains released and its contact 37 interrupts the clear or proceed operating circuit of the signal 4S, while contacts 34 and 35 of relay 4DP continue to interrupt the circuit short circuiting the winding of the inductor 4K.

When the train vacates section 5T track relay 5TR picks up and its contact 38 establishes the caution operating circuit for signal 5S and signal controlled contact 25 closes and cooperates with contact 39 of relay 5TR to establish connection from terminal B of battery 5M to wire 28 leading to relay 4DR. Accordingly, energy is supplied from battery 5M over wires 28 and 10 to relay 4DR and the contacts of this relay pick up so that energy is supplied from battery 4M to relay 4DP over the circuit which is traced from terminal B through front contact 31 of relay 4DR, winding of inductor 4K, front contact 32 of relay 4DR, winding of relay 4DP, and wire 10 to terminal C.

If the circuit of the inductor winding is intact, the relay 4DP will be energized in series with the inductor winding and the contacts of relay 4DP will pick up so that contact 37 establishes the clear operating circuit for signal 4S, while contacts 34 and 35 short circuit the winding of inductor 4K and establish connections shunting the inductor winding for energizing the winding of relay 4DP. The signal 4S, therefore, displays its clear or proceed indication while the circuit of the inductor winding is short circuited.

If, at the time the train vacates section 5T and the contacts of relay 4DR pick up, the circuit of the winding of the inductor 4K is defective, en-

ergy will not be supplied to the winding of the relay 4DP and the contacts of this relay will remain released so that the clear operating circuit of the signal 4S is not established and the signal continues to display its caution indication, and contacts 34 and 35 of relay 4DP do not short circuit the winding of the inductor 4K. Accordingly, a following train will receive a caution indication from signal 4S while the inductor 4K will cause an application of the train brakes.

It will be seen, therefore, that the system shown in Fig. 2 is arranged so that the circuit of the winding of the inductor associated with each section is checked every time a train passes through the track section, and if the winding is defective the associated signal cannot be conditioned to display its clear indication.

The modifications shown in Figs. 1 and 2 are arranged so that the circuit of the winding of each inductor is checked immediately after passage of a train, and if a defect in an inductor winding develops after the circuit of the winding has been checked it will not be discovered until after the passage of another train.

The modification shown in Fig. 3 is similar to that shown in Fig. 2, but differs therefrom as it is arranged so that the circuit of the winding of the inductor for each section is checked immediately before entrance of a train into the section.

The modification shown in Fig. 3 employs a searchlight signal of the type shown in Letters Patent of the United States No. Re. 14,940 issued to E. J. Blake, while this modification employs an approach relay AR which governs the circuit of the lamp L of the associated signal and also governs the circuit of the relay DP. Each signal includes a contact Y which is operated by the signal mechanism and controls the circuit of the relay AR so that this relay may be energized when the signal is conditioned to provide its yellow indication and is deenergized when the signal displays its red or its green indication.

The equipment is shown in the condition which it assumes when the track stretch is vacant. At this time the track relays TR are picked up and the relays 5AR and 4DR are energized in series over the circuit which is traced from terminal B of battery 5M, wire 11, winding of relay 5AR, front contact Y of signal 5S, front contact 39 of relay 5TR, wire 28, front contact 39 of relay 4TR, winding of relay 4DR, and wire 10 to terminal C of the battery 5M. Accordingly, the contacts of relay 5AR are picked up and its contact 41 interrupts the circuit of the lamp L of signal 5S, while its contact 42 interrupts the circuit of the relay 5DP so that the contacts of this relay are released and its contacts 36 and 37 cause the energy supplied to the operating winding of the signal 5S to be of the polarity effective to cause the signal to display its yellow or caution indication. The circuit for supplying energy to the signal winding is traced from terminal B of the battery 5M through wire 11, front contact 38 of relay 5TR, back contact 37 of relay 5DP, winding of the signal, back contact 36 of relay 5DP, and wire 10 to terminal C.

As the relay 4DR is energized its contacts 31 and 32 are closed to permit energy to be supplied to the relay 4DP, but at this time the supply of energy to this relay is interrupted by contact 42 of relay 4AR so relay 4DP remains released and its contacts 34 and 35 do not short circuit the winding of the inductor 4K, while its contacts 36 and 37 cause the energy supplied to the operating winding of signal 4S to be of the polarity

effective to cause the signal to display its caution indication.

At this time relay 5DR is energized in series with the approach relay for the section in advance, while the relay 4AR is energized over a circuit similar to that traced for relay 5AR.

When a train moving from left to right enters section 3T the track relay, not shown, for this section releases and its contact 39 interrupts the circuit for energizing the relay 4AR in series with the relay 3DR, not shown. Accordingly, the relay 4AR releases and its contact 41 establishes the circuit of the lamp L of signal 4S, while its contact 42 establishes the circuit to energize relay 4DP in series with the winding of the inductor 4K. This circuit is traced from terminal B of battery 4M, through wire 11, back contact 42 of relay 4AR, front contact 31 of relay 4DR, winding of inductor 4K, front contact 32 of relay 4DR, winding of relay 4DP, and wire 10 to terminal C of the battery.

If the circuit of the inductor winding is intact, the relay 4DP will be energized in series with the inductor winding and the contacts of the relay 25 will pick up and short circuit the inductor winding and establish a path shunting the inductor winding for energizing the relay winding. In addition, on picking up of the relay contacts its contacts 36 and 37 change the polarity of the energy supplied to the winding of signal 4S so that the signal is conditioned to display its green or clear indication.

On this change in the aspect of the signal contact Y of the signal is opened and interrupts the 35 circuit of the approach relay 4AR to insure that this relay remains released and maintains the circuit of the relay 4DP.

If at the time the train enters section 3T and relay 4AR releases the circuit of the winding of 40 inductor 4K is defective, the relay 4DP will remain released and its contacts 36 and 37 will maintain the supply of energy to the signal winding of the polarity effective to cause the signal to provide its yellow or caution indication, while 45 contacts 34 and 35 of the relay do not short circuit the inductor winding. Under these conditions, therefore, the train approaching signal 4S will receive a caution indication from this signal, while the inductor 4K will cause the train-carried apparatus to provide a brake application unless it is suppressed by the engineer.

When the train advances into section 4T track relay 4TR releases and its contact 39 interrupts the circuit for energizing the relays 4DR and 5AR in series, and the relay 5AR releases to establish the circuit of the lamp L of signal 5S, and to also establish the circuit for energizing the relay 5DP in series with the winding of inductor 5K so that this relay changes the polarity of the energy supplied to the winding of the signal 5S to thereby cause this signal to provide its green or clear indication, while contacts 34 and 35 of relay 5DP short circuit the inductor 5K.

In addition, on release of track relay 4TR its contact 39 interrupts the circuit for energizing the relay 4AR in series with the relay DR, not shown, associated with the adjacent signal in the rear. This insures that the relay 4AR will remain released and maintain the circuit of the lamp L of signal 4S. Release of contact 38 of track relay 4TR interrupts the supply of energy to the operating winding of signal 4S so that the signal displays its red or stop indication.

Release of contact 38 of relay 4TR interrupts the circuit of relay 4DR, as explained above, and

contacts 31 and 32 of this relay interrupt the circuit of relay 4DP so that the contacts 34 and 35 of this relay remain released so that the winding of the inductor 4K is open circuited, while contacts 36 and 37 of relay 4DP are released so that on subsequent picking up of the track relay contacts the energy supplied to the operating winding of the signal 4S is of the polarity effective to cause the signal to display its yellow or caution indication.

Similarly, when the train enters section 5T and track relay 5TR releases relays 5AR and 4DR are maintained released, while the supply of energy to the winding of the signal 5S is interrupted so that the signal displays its stop indication. In addition, release of relay 5TR interrupts the circuit of the relay 5DR and the contacts of this relay release and interrupt the circuit of the relay 5DP.

When the train vacates section 3T the track relay, not shown, for that section picks up, but at this time the circuit of relay 4AR is also interrupted by contact 39 of relay 4TR so relay 4AR remains released and maintains the supply of energy to the lamp L of signal 4S.

When the train vacates section 4T track relay 4TR picks up and its contact 39 completes the circuit for energizing the relay 4AR in series with the relay DR of the adjacent signal in the rear. Accordingly, the relay 4AR picks up and its contact 41 interrupts the circuit of the lamp L of signal 4S, while contact 42 prevents the supply of energy to the relay 4DP.

In addition, on picking up of the contacts of track relay 4TR its contact 38 establishes the circuit for supplying energy to the winding of the signal 4S. At this time the contacts 36 and 37 of relay 4DP are released so that the energy supplied to the signal winding is of the polarity effective to cause the signal, when lighted, to display its yellow or caution indication.

On picking up of the contacts of track relay 4TR its contact 30 is closed to permit energy to be supplied to the relay 4DR. At this time, however, section 5T is occupied and relay 5TR is released so that its contact 39 interrupts the circuit of the relay 4DR and this relay remains released and prevents energization of the relay 4DP.

It will be seen, therefore, that when a section is vacated the lamp of the signal for that section is extinguished, while energy is supplied to the winding of the signal to condition it when lighted to display its yellow or caution indication. In addition at this time relays DR and DP remain released so the inductor winding is open circuited.

Accordingly, if while section 5T is occupied, a second or following train enters section 3T, the track relay for this section will release and interrupt the circuit of relay 4AR so that this relay releases and its contact 41 establishes the circuit of the lamp L of signal 4S. This signal, therefore, will display its yellow or caution indication.

On release of relay 4AR its contact 42 closes, but at this time relay 4DR is released, as explained above, so energy is not supplied to relay 4DP and this relay remains released so the winding of the inductor 4K is open circuited, and if the train passes over the device the brakes on the train will be applied unless prevented by the engineer from doing so.

If the second or following train enters section 4T, track relay 4TR will release and interrupt the supply of energy to the winding of signal 4S so that this signal displays its red or stop indication.

On release of track relay 4TR its contact 30 interrupts the circuit for energizing relays 4DR and 5AR in series, but this circuit is already interrupted by contact 39 of relay 5TR and by contact Y of signal 5S so opening of contact 30 of relay 4TR is without effect.

When the first train vacates section 5T the equipment associated with this section operates in the same manner as that associated with section 4T so that energy is supplied to the winding of the signal 5S to condition it when lighted to provide its yellow or caution indication.

As track relay 5TR is picked up and as the contact Y of the signal 5S is closed, and assuming section 4T to be unoccupied, the circuit for energizing the relays 5AR and 4DR in series is established and the contacts of these relays pick up. On picking up of the contacts of relay 5AR its contact 41 interrupts the circuit of the lamp L of signal 5S, while on picking up of the contacts of relay 4DR its contacts 31 and 32 are closed to permit energy to be supplied to relay 4DP on subsequent release of the contacts of relay 4AR.

From the foregoing it will be seen that the modification shown in Fig. 3 is arranged so that the relays DP which control the green or clear signal indications also control the circuits of the inductor windings. It will be seen also that the energy to pick up the contacts of the relays DP is supplied through the inductor windings so that these relays will not pick up to change the signal aspect from caution to clear unless the circuits of the inductors are intact.

In addition, it will be seen that the circuit of the relay DP for each signal is governed by the approach relay for that signal so that the relay DP for each section is released until the adjacent section in the rear is occupied. Accordingly, the circuit of the winding of the inductor for each section is checked immediately prior to passage of a train over the inductor. This substantially eliminates the possibility that a defect will develop in the circuit of the inductor winding subsequent to picking up of the relay DP and prior to the passage of a train over the inductor.

It will be seen also that the modification shown in Fig. 3 is arranged so that when the contacts of the relay DP are released the wires leading to the winding of the associated inductor are isolated from the signal control circuits so that a defect in these circuits will not result in short circuiting of the inductor winding.

Although I have herein shown and described only three forms of railway signaling systems embodying my invention, it is understood that various changes and modifications may be made therein within the scope of the appended claims without departing from the spirit and scope of my invention.

Having thus described my invention, what I claim is:

1. In a railway signaling system, in combination, a section of railway track, a signal at the entrance of said section capable of displaying a stop and a proceed indication, a trackway device at the entrance of said section adapted to cooperate with train-carried apparatus, said trackway device having a core and a winding, a relay, a source of current, means for connecting one terminal of the winding of said relay to one terminal of said source, means governed by traffic conditions in said section for connecting the other terminal of the relay winding to one terminal of the winding of the trackway device and for connecting the other terminal of the winding of the

trackway device to the other terminal of said source, means effective when said relay is energized to condition said signal to provide its proceed indication, and means effective when said relay is energized to short circuit the winding of said trackway device.

2. In a railway signaling system, in combination, a section of railway track, a signal at the entrance of said section capable of displaying a stop and a proceed indication, a trackway device at the entrance of said section adapted to cooperate with train-carried apparatus, said trackway device having a core and having a winding having a first and a second terminal, a relay effective when energized to condition the signal to provide its proceed indication, said relay having a normally released movable contact which when the relay winding is energized is moved into engagement with a stationary contact, the winding of the trackway device having one of its terminals connected to one of said relay contacts and having its other terminal connected to the other relay contact, a source of current, means for connecting one terminal of the winding of said relay to one terminal of said source, and means governed by traffic conditions in said section for establishing connection from the other terminal of the relay winding to the first terminal of the winding of said trackway device and for establishing connection from the second terminal of the winding of said trackway device to the other terminal of said source.

3. In a railway signaling system, in combination, a section of railway track, a signal at the entrance of said section capable of displaying a stop and a proceed indication, a trackway device at the entrance of said section adapted to cooperate with train-carried apparatus, said trackway device having a core and having a winding having a first and a second terminal, a relay effective when energized to condition the signal to provide its proceed indication, said relay having a normally released movable contact which when the relay winding is energized is moved into engagement with a stationary contact, the winding of the trackway device having one of its terminals connected to one of said relay contacts and having its other terminal connected to the other relay contact, a source of current, means for connecting one terminal of the winding of said relay to one terminal of said source, and means governed by traffic conditions in said section and in the adjacent section in advance for establishing connection from the other terminal of the relay winding to the first terminal of the winding of said trackway device and for establishing connection from the second terminal of the winding of said trackway device to the other terminal of said source.

4. In a railway signaling system, in combination, a forward and a rearward section of track, a signal at the entrance end of said rearward

section capable of displaying a stop and a proceed indication, a trackway device at the entrance of said rearward section adapted to cooperate with train-carried apparatus, said trackway device having a core and a winding, a first and a second relay, means effective when said forward and rearward sections are both vacant to supply energy to said first relay, the second relay having a movable contact which when picked up engages a stationary contact, the winding of the trackway device having one of its terminals connected to one contact of said second relay and having its other terminal connected to the other contact of said second relay, a source of current, means for connecting one terminal of the winding of said second relay to one terminal of said source, a contact of said first relay being effective when the relay is energized to connect the other terminal of the winding of the second relay to one terminal of the winding of the trackway device, another contact of said first relay being effective when the relay is energized to connect the other terminal of the winding of the trackway device to the other terminal of said source, and means effective when said second relay is energized to condition said signal to provide its proceed indication.

5. In a railway signaling system, in combination, a forward and a rearward section of track, a signal at the entrance end of said rearward section capable of displaying a stop and a proceed indication, a trackway device at the entrance of said rearward section adapted to cooperate with train-carried apparatus, said trackway device having a core and a winding, a first and a second relay, means effective when said forward and rearward sections are both vacant to supply energy to said first relay, the second relay having a movable contact which when picked up engages a stationary contact, the winding of the trackway device having one of its terminals connected to one contact of said second relay and having its other terminal connected to the other contact of said second relay, a source of current, means for connecting one terminal of the winding of said second relay to one terminal of said source, a contact of said first relay being effective when the relay is energized to connect the other terminal of the winding of the second relay to one terminal of the winding of the trackway device, another contact of said first relay being effective when the relay is energized to connect the other terminal of the winding of the trackway device to the other terminal of said source, means effective when said second relay is energized to condition said signal to provide its proceed indication, and means effective when the section in the rear of said rearward section is vacant to interrupt the circuit of said second relay.

HENRY S. YOUNG.
